CASTING WITH INTEGRAL SPRAY JETS

Joseph W. Jagersberger and Richard D. Miller,
Racine, Wis.

Application August 28, 1941, Serial No. 408,572

8 Claims. (Cl. 123—173)

This invention relates to improvements in castings with integral spray jets.

The present invention, although not limited thereto, is particularly applicable to internal combustion engines of the valve-in-the-head type wherein it is desirable that the cooling liquid for the engine be sprayed onto walls surrounding or adjacent the exhaust valve seats. The present design of valve-in-the-head engines is such that there is a water jacket in the engine head, which head also contains the exhaust valves and exhaust valve seats, but without the employment of special means insufficient cooling liquid will reach the walls in which the exhaust valve seats are formed, whereby said parts will become unduly heated to the detriment of the moving parts and efficient operation of the engine.

In the past there has been attempted a rather make-shift arrangement for overcoming this difficulty and for spraying cooling liquid on the exhaust valve seat containing walls of a valve-in-the-head engine. According to said arrangement the engine head was cast in the usual manner and of the usual metal. Openings were drilled through the bottom of the head adjacent the combustion chamber and exhaust valve seats, providing ducts between the main cylinder block water jacket and the lower portion of the water jacket of the head. Into these drilled openings or ducts were inserted, so as to have force fits, tubular jets or spray members having apertured upper ends arranged to spray cooling liquid on the desired wall surfaces of the engine head adjacent the exhaust valve seats, said jets or spray members being formed of copper, steel, or some suitable metal different from that of the engine head casting.

With respect to the prior arrangement just noted, objections are found in the fact that the forming and insertion of separate spray jets or nozzles requires additional operations and is relatively expensive. Also, by virtue of the fact that the metals of the head and spray jets are different, said respective members have a different coefficient of expansion and loosening of the spray jets is possible. Additionally, because of the different metals the spray jets may be adversely affected by anti-freeze solutions used in the cooling liquid in winter. It should further be noted that during the present national emergency metals such as copper, brass, steel, etc. are unattainable for normal, non-defense purposes and this presents a problem which renders the prior arrangement objectionable.

It is, therefore, a primary object of the present invention to overcome the above objections and

difficulties by providing a valve-in-the-head internal combustion engine with integrally cast valve seat spray jets, whereby the jets are of the same metal as the engine head, extra operations and assembly steps in the manufacture are eliminated, and the spray jets can not become loosened or be otherwise affected.

A further object of the invention is to provide a casting with an integral spray jet positioned and constructed so as to effectively direct a spray or stream of cooling liquid on portions of the casting which would otherwise tend to become overheated during usage.

A further object of the invention is to provide a casting with an integral spray jet which is very simple and inexpensive in construction, which eliminates the use of metals difficult to obtain, and which is efficient and automatic in operation.

A further object of the invention is to provide integral spray jets in an internal combustion engine head wherein bosses with mutilated or irregular outer ends are cast integral with the head and are drilled to provide ducts through the bosses and offset discharge orifices in the irregular outer ends of the same.

A further object of the invention is to provide a casting with integral spray jets which is simple, inexpensive, and well adapted for the purposes described.

With the above and other objects in view the invention consists of the improved casting with integral spray jets, and its various parts, and combinations, as set forth in the claims, and all equivalents thereof.

In the accompanying drawing in which the same reference characters indicate the same parts in all of the views:

Fig. 1 is a transverse fragmentary vertical sectional view through the cylinder block and head of a valve-in-the-head internal combustion engine, showing the present improvements;

Fig. 2 is a horizontal sectional view taken on the irregular line 2—2 of Fig. 1;

Fig. 3 is a horizontal sectional view taken on line 3—3 of Fig. 1;

Fig. 4 is a fragmentary detail sectional view showing that portion of the cylinder head which has a boss cast thereon for the formation of a spray jet, the view illustrating the principal form of the invention and prior to the drilling operation;

Fig. 5 is a fragmentary detail sectional view similar to Fig. 4 only showing the completion of the drilling operation relative to the integrally cast boss; and

Fig. 6 is a fragmentary detail sectional view similar to Fig. 5 only showing the drilling operation of a modified form of integral boss.

Referring now more particularly to the drawing, wherein the invention, by way of illustration, is incorporated in an internal combustion engine of the valve-in-the-head type, it will be noted that the cylinder block 10 encloses a plurality of cylinders 11 having reciprocatable pistons 12 therein. As is usual, the cylinder block is provided with a water jacket or internal passages 13 for the circulation of a cooling medium or fluid about the cylinders.

The top of the cylinder block 10 is closed and covered by a cylinder head 14 which is bolted onto the upper surface of the cylinder block 10. Within the cylinder block over each cylinder 11 is a combustion chamber 15 from which the escape of exhaust gases is controlled by a valve 16 carried by the lower end of a slideable valve stem 17. Each valve 16 is adapted to be moved to open and closed position relative to an annular valve seat 18 in an interior wall or partition of the head 14. Within the engine head 14 there are also lower water jackets or passageways 19 for the circulation therethrough of a cooling medium. From Fig. 1 it will be observed that the walls surrounding the valve seat 18 are relatively thick and are not in the direct path of cooling medium circulating in the jacket or passageways 19. In actual practice, without the provision of special means, in an internal combustion engine of the type under consideration, the walls surrounding the valve seats 18 become excessively heated and may become scored or otherwise damaged. Hence, a specific object of the present invention is to provide effective integral means for insuring the introduction of a cooling medium directly onto the wall surfaces surrounding the exhaust valves 18 so as to keep said surfaces and the valve seats efficiently cooled.

On opposite sides of a valve seat the cylinder head 14 is cast with integral bosses 20, which bosses extend upwardly from the lower wall of the head 14 into portions of the jacket 19. The bosses are cast at the time of casting the head 14 and are accomplished during the molding operation by means of a jacket core box, the bosses being of the same metal as that of the head proper, which is customarily iron.

From Fig. 2 it will be observed that each boss is positioned so as to serve a pair of exhaust valve seats for adjacent cylinders. The upper end of each boss is cast in a stepped or mutilated condition as indicated at 21, with said stepped portions facing the convergence of the adjacent cylinders which it is to serve.

Following the casting operation the bosses are drilled, as will be described more fully hereinafter, to provide longitudinal ducts 22 therethrough terminating in angular discharge orifices 23 at the mutilated or stepped ends. Each drilled opening through a boss thereby affords direct communication between an upper outlet opening 24 in the cylinder block between the jacket 13 and the internal cooling fluid passage 19 in the cylinder head 14.

In the operation of an internal combustion engine provided with the present improvements, the engine operates in the usual way and a cooling medium or fluid is circulated through the passageway or water jacket 13 of the cylinder block. This fluid is forced upwardly through the drilled openings 22 in the bosses or spray jets 20 and discharges in the form of sprays or

streams from the orificed angled upper discharge ends of the same. These discharge ends are positioned in the manner shown in Figs. 1 and 2 so that wall portions surrounding the exhaust valve seats 18 are effectively constantly sprayed with the cooling medium, which is directed in the manner shown in Figs. 1 and 2.

From the description thus far it will be apparent that the spray jets 20 are integral with the cylinder head 14 and are formed of the same material as the cylinder head. Hence, during usage, said members can never become loosened and also will not be injuriously affected by any anti-freeze solution in the cooling medium.

As was previously mentioned, the bosses 20 are formed during the casting of the cylinder head and are cast in solid form in the shape illustrated with stepped or mutilated upper side portions. To render the same tubular and to provide the discharge orifices, each boss, originally in the condition shown in Fig. 4, is operated on by a drill having a conical end. As is shown in Fig. 5, the drill works from the bottom of the boss upwardly in a rectilinear path and the drilling operation is terminated before the drill penetrates the upper extremity of the boss, but after the drill has broken through or penetrated the stepped or mutilated upper side portion of the boss. This, therefore, provides the angularly disposed discharge orifice at the outer end of a boss, as is mostly clearly shown in Fig. 5. While the formation of a duct through a boss is shown as being accomplished with a drill, it is obvious that it may be carried out through the use of any suitable tool.

A slight modification is illustrated in Fig. 6 wherein a boss 20' on a portion of the casting 14 is originally cast with an inclined or tapered upper side face 21' instead of the specific stepped side face of Figs. 4 and 5. This boss is completed in a similar manner by the use of a drill with a conical end with the drilling operation terminating after the drill breaks through the inclined side face 21', but before the drill reaches the extreme upper end of the boss 20'.

The invention is particularly applicable to castings of any type, especially engines, where it is desirable to direct a spray or stream of a cooling fluid onto some particular internal portion of a casting which would otherwise tend to heat up excessively. The improved castings with integral spray jets, are simple and commercially practical and are well adapted for the purposes set forth.

What is claimed as the invention is:

1. A metal casting formed with an internal chamber, and a spray nozzle of the same metal as the casting formed at one end integrally with a wall portion of said casting and projecting into said chamber, the projecting end portion of the nozzle being mutilated and having an angularly directed discharge orifice therein.

2. A metallic cylinder head having internal walls forming a water jacket, one of said walls having an opening therein to provide a valve seat, and a spray nozzle formed at one end integrally with a wall portion of said cylinder head and projecting into the water jacket adjacent said valve seat, the projecting end portion of the nozzle being of irregular contour and having an angularly directed discharge orifice therein to discharge a cooling medium adjacent said valve seat.

3. A valve-in-the-head internal combustion engine, comprising a cast metal cylinder block

enclosing cylinders surrounded by a water jacket, a cast metal cylinder head mounted on the cylinder block and having internal walls forming an upper water jacket, certain wall portions above the cylinders being formed with valve seats, valves movable relative to said seats, and metal spray nozzles formed at their lower ends integrally with lower wall portions of said cylinder head and projecting into the upper water jacket adjacent said valve seats to discharge sprays of water there-adjacent, each nozzle forming a communication between the lower and upper water jackets.

4. A valve-in-the-head internal combustion engine, comprising a cast metal cylinder block enclosing cylinders surrounded by a water jacket, a cast metal cylinder head mounted on the cylinder block and having internal walls forming an upper water jacket, certain wall portions above the cylinders being formed with pairs of adjacent valve seats, valves movable relative to said seats, and metal spray nozzles formed at their lower ends integrally with lower wall portions of said cylinder head and projecting into the upper water jacket, each nozzle being substantially equidistant between the valve seats of an adjacent pair and having an angular upper discharge orifice to spray water adjacent both of said seats, each nozzle forming a communication between the lower and upper water jackets.

5. A metal casting formed with an internal chamber, and a spray nozzle formed at one end integrally with a wall portion of said casting and projecting into said chamber, the projecting end portion of the nozzle being stepped, there being a bore in said nozzle terminating in a conical recess in the projecting end of the nozzle and opening through the stepped end portion thereof to provide an angularly directed discharge orifice.

6. A metal casting formed with an internal chamber, and a spray nozzle formed at one end integrally with a wall portion of said casting and projecting into said chamber, the projecting end portion of the nozzle having an upper side face portion thereof tapered, there being a bore in said nozzle terminating in a conical recess in the projecting end of the nozzle and opening through said tapered face portion to provide an angularly directed discharge orifice.

7. A metal casting formed with an internal chamber, and a spray nozzle formed at one end integrally with a wall portion of said casting and projecting into said chamber, the projecting end portion of the nozzle having an angular side wall, there being a bore in said nozzle terminating in a recess in the projecting end of the nozzle and opening through said side wall of the nozzle to provide a discharge orifice, the plane of a portion of said opening being at an angle to the axis of the nozzle bore and the entire opening being laterally of the plane of the axis of said bore.

8. A metal casting formed with an internal chamber, and a spray nozzle of the same metal as the casting formed at one end integrally with a wall portion of said casting and projecting into said chamber, the projecting end portion of the nozzle being of irregular contour, there being a bore in said nozzle and there being a discharge orifice in a portion of the projecting end of the nozzle on one side of the plane of the axis of the nozzle bore and with which said bore communicates, the projecting end of the spray nozzle on the other side of the plane of the axis of the bore being closed to partially cap the end of the nozzle bore.
